WRINGER AND DRAINBOARD APPARATUS

John C. Clapper and David A. Constance,
Altoona, Pa.

Application July 31, 1937, Serial No. 156,821

2 Claims. (Cl. 68—248)

The present invention relates to washing machines and more particularly to a novel wringer and drainboard relationship. The wringer and drainboard arrangement to be disclosed herein is adaptable for use in conjunction with washing machines of the domestic type or in association with commercial laundry equipment.

An object of the invention is to provide a safe, simple wringer and drainboard arrangement in order that an operator, standing in any position about the wringer, may quickly feed through said wringer a large quantity of washed material without fear of injury to the operator.

Another object of the invention resides in the use of horizontally disposed rollers which may turn in either direction, to facilitate the progress therethrough of the material to be wrung out and at the time provide for disposal of the water passing from the material effected by the wringing action of the rollers.

Other objects and advantages will become apparent in view of the following description taken in conjunction with the drawing, wherein:

Fig. 1 is an elevation of a domestic type of washing machine disclosing a rear view of the combination guide member and drainboard;

Fig. 2 is also an elevation showing a side view of the same;

Fig. 3 is a top plan view showing the disposal of the rollers, the drainboard, and their relationship to the tub;

Fig. 4 is a cross sectional view in detail of the rollers and the drainboard, the drainboard being shown in an alternate position in broken lines; and,

Fig. 5 is a view in perspective partially in cross section showing one form of drainboard that might be used as an element in our novel arrangement.

Referring to the drawing, a domestic type washing machine 10 having casters or wheels 11 providing for the portability of the device in the usual manner, is depicted as having a casing 12 for housing driving mechanism for operating a vertically aligned shaft, within a tubular housing 13, which shaft engages a driving train within a protecting casing 14 which is operatively connected to a roller 15. A cooperating roller 16 is provided for association with the roller 15.

Said rollers are mounted on bracket member 17 having suitable bearings therein for the reception of shaft portions 18 lying in the same horizontal plane. Revoluble supports 19 supported on the bracket member 17 are mounted for rotation about an axis passing through said

bracket member and having secured thereto at their lower ends supporting bar 20 to which is secured by suitable fastening means a guide member and drainboard.

As more clearly shown in Fig. 4 a spring means 22 is secured on said bracket members 17 in a suitable manner for engaging the pin member 23 on said revoluble supports 19 in order that the drain and guide board 21 may be supported in a position above the roller 16 when the said rollers are so operated to pass clothes, about to be wrung out, upwardly through the passage between said rollers.

The spring means 22 comprises a conventional leaf spring as illustrated in Fig. 4, bent as shown to securely engage and hold the pin member 23 secured to the revolable support 19 when same is moved to its upper position as is also illustrated. The frictional engagement between the pin member 23 and leaf spring 22 is such as normally to hold the guide member 21 in the position shown in dot and dash lines in this figure, but not great enough to prevent the rotation of the arm 19 by the operator to release the pin 23, whereby the guide member 21 may take the position shown in full lines.

A feed baffle member 24 is hingedly supported at 24a on the rear portions of bracket member 17 in such a manner that when said baffle member is arranged in its highest position and said rollers 16 are operating to pass clothes upwardly therebetween, then clothes will be fed from roller 16 and on to the drainboard and guide member 21.

The drainboard and clothes guide 21 comprising a flat sheet like body portion with its opposite side flanged upwardly to provide guide portions may have a series of perforations 25 therein arranged in a geometrical or other pattern or they may take the form of that in drainboard 21', as depicted in Fig. 5, showing lateral slit-like 40 perforations 26, each of said perforations being provided with a depending lip portion 27. The drainboard and guide member may be coated with any suitable material.

A handle member 28 is provided on protecting housing 14 to permit arranging gears therein for operation of the rollers in such direction that clothes may pass therethrough downwardly or upwardly.

With the drainboard 21 in position beneath 50 the wringer rollers 15 and 16, and with the handle 28 so set that the wringer rollers will operate to pass clothes therethrough downwardly, an operator may then, from any position about the wringer rollers, without special care being taken 55

to protect himself or herself from the action of said rollers, merely place clothes upon the two rollers which will then engage the clothes to be wrung out, wring them out and pass them on 5 to the drainboard and clothes guide 21. Water wrung out from said clothes will pass through the perforations 25 back into the tub of the washing machine, the clothes passing on and down the guide member into a clothes basket or 10 other receptacle, not shown, which may be there provided for the reception of wrung out clothes or other material.

When the wringer is to be arranged so that the rollers pass wet clothes therebetween in an upward direction, then the drain and guide board 15 21 is swung out and above the roller 16 in a manner to cause the pins 23 to engage the spring members 22 locking the drainboard and guide member 21 in its upper position. The hinged 20 baffle member 24 is then swung about to its upper position. The operator may then simply reach for clothes that have been washed in the tub and place them in proximity to the lower portion of the line of contact between the two rollers, 25 the clothes will then be wrung out and passed upwardly and by the operation of the baffle member 24 the clothes will be urged over perforated drainboard and guide member 21 from whence they may pass to the clothes basket or other receiving means provided for that purpose.

The drainboard 21' has been designed particularly for use with the arrangement just disclosed. Clothes passing through the rollers in the manner heretofore described and fed on to 35 said drainboard 21' pass downwardly also in the manner already described. Water wrung out from said clothes, however, will adhere to the surface of the drainboard and guide member and by capillary attraction will seek the lower edges 40 of the lips 27 and drip therefrom back to the tub beneath. The wrung out clothes will thereby be sufficiently dry and effectively separated from the wrung out water.

Previously, operators of wringers having dual 45 rollers have found when using wringers having vertically disposed rollers that they must assume a certain position relative to said rollers and that much caution must be exercised in order to prevent portions of the person from being engaged between the wringing surfaces of the rollers during their operation, for the wet material must be fed horizontally and sometimes started by 50 pressing the said material between the rollers with the fingers. This fact is evidenced by the 55 appearance on the market of many safety devices for ceasing action of said rollers when a finger of the operator or other foreign member is engaged between the operating portions of the 60 rollers. Though such safety devices may be incorporated in a clothes washer and wringer, embodying our invention, it is believed that the need for such safety devices is lessened by our novel and advantageous arrangement.

65 In accordance with our invention, it is to be

understood that the bracket member 17 and casting 14 may be pivotally connected with tubular housing 13 and hence may be swung about in a complete circle, if necessary, whereby a single wringer and drainboard outfit will suffice to complement a plurality of tubs. When the bracket member is so mounted, a suitable key or lock, not shown, may be provided to lock bracket member 17 to housing 13 in any operative position.

It will be obvious to those skilled in the art that various changes may be made in our device without departing from the spirit of the invention and therefore we do not limit ourselves to what is shown in the drawing and described in 15 the specification but only as indicated in the appended claims.

We claim:

1. A wringer and drainboard assembly comprising a frame, substantially horizontally disposed substantially parallel rollers mounted in said frame, the axes of which rollers lie in substantially the same horizontal plane, an inclined perforated drainboard of appreciable length suspended from said frame by swingable linkage 20 means near the upper end thereof and adapted to be supported near its other end, said linkage being selectively operable to permit the upper end of said drainboard to be positioned below the plane of said rollers and the same end to be positioned above said plane, holding means associated with said assembly for holding said drainboard in secure position with one of its ends positioned above the axis of said rollers, whereby when said drainboard is in its first position with respect to 30 the rollers clothes to be wrung out may be fed to the upper surface of said rollers and passed therethrough on to the drainboard, the water from the wrung out clothes passing through the perforations in the drainboard and the relatively 40 dry clothes moving on along the drainboard to a receptacle which may be placed below the lower end thereof, and when said drainboard is in said second position, clothes to be wrung out may be fed to the lower surface of said rollers, passed 45 upwardly through the rollers and on to the drainboard.

2. The structure recited in claim 1, and a baffle member hingedly mounted on said wringer assembly and operable to be swung to an upward 50 baffling position when one end of said drainboard is in position above the axis of said rollers, whereby clothes to be wrung out fed upwardly through said rollers will be urged to move on to said drainboard, said baffle member being further 55 operable to be swung to a lower out of the way position when the upper end of said drainboard is mounted below the axis of the said rollers, whereby substantially the entire upper surfaces of the rollers are free for the application thereto 60 of clothes to be wrung out and passed on to said perforated drainboard.

JOHN C. CLAPPER.
